UNITED STATES PATENT OFFICE.

JACOB HENRY STULL, OF FREMONT, OHIO.

LEAD-PENCIL.

1,361,115.

Specification of Letters Patent.

Patented Dec. 7, 1920.

Application filed June 19, 1919. Serial No. 305,340.

To all whom it may concern:

Be it known that I, JACOB H. STULL, a citizen of the United States, residing at Fremont, in the county of Sandusky and State of Ohio, have invented certain new and useful Improvements in Lead-Pencils; and I do declare the following to be a full, clear, and exact description of the invention, such as will enable others skilled in the art 10 to which it appertains to make and use the same.

This invention relates to lead-pencils, and it relates more specifically to an improved point projecting device in the class of pencils in which the pencil-points or marking elements are movable outward by a manipulative or movable part of the pencil.

One object of this invention is to generally improve upon devices of this character while providing an improved structure in which the pencil-points are projected and held by an elastic element which is accurately guided, in alinement with the pencil points, by a collar which surrounds the 25 elastic element.

Other objects and advantages may become apparent to persons who read the following details of description in connection with the accompanying drawings, in which:—

30 Figure 1 is a side elevation of a pencil constructed according to the present invention.

Fig. 2 is a vertical longitudinal sectional view which discloses the internal mechanism of the pencil.

Fig. 3 is a transverse sectional view along the line 3—3 of Fig. 2.

Fig. 4 is a transverse sectional view along the line 4—4 of Fig. 2.

40 Fig. 5 is a detail sectional view illustrating a somewhat modified form of the pencil-point receptacle.

Referring to these drawings in detail, in which similar reference characters correspond with similar parts throughout the several views,—

The device comprises a casing 6 having a tapering front end portion which has an opening or outlet 7 therein, said outlet consisting of a narrow bore or tubular element in which a pencil-point or lead 8 is seated, the bore of the outlet being frictionally engaged with the pencil-point or lead so as to prevent it from dropping out of the outlet 7, but being longitudinally movable in the outlet 7 so that it may be easily pro-

jected by means of a plunger or pusher 9 which is preferably formed integrally with a helical coil or spring 10 and extends in axial alinement with the coil, it being understood that this wire extends radially inward at 11, and it may also be extended radially inward at 12 for a purpose which will hereinafter appear.

A sleeve or annular guide 13 is secured 65 by any suitable means to the inner surface of the casing 6, and this sleeve is preferably formed with an integral lug 14 which extends radially inward between two helices of the coil 10, and said coil is slidably engaged with the inner surface of the sleeve 13, so that the coil may be rotated and moved longitudinally in the sleeve. A manipulative actuator 15 is formed with a barrel 15^a which is rotatably mounted within 70 the rear end of the casing 6, suitable means being provided, as indicated at 16, for preventing longitudinal movement of the actuator with relation to the casing. The rear part of this manipulative actuator is formed 75 with an annular manipulative element 15^b which has a circular opening 15^c through its extreme rear end. A longitudinally grooved rod 17 has its rear end united with the bottom or front end of the hollow 80 manipulative member 15, and this grooved rod is provided with an axial bore 18 which is in open communication with the longitudinal groove 19 of the rod 17. In other words, the groove 19 extends inward past 85 the axial center of the rod 17, so that its inner surface is flush with the axial bore 18, as clearly shown in Fig. 3. The grooved rod 17 extends through the helical coil 10, and the external diameter of the rod is so 90 near the internal diameter of the coil 10 that the sleeve 13 and coil 10 coöperate with the actuator 15 for holding the rod 17 and pusher 9 in axial alinement with the pencil-point 7.

100 It will be seen, therefore, that when the actuator 15 is rotated, the rod 17 is thereby rotated, and the engagement of this rod with the inwardly extending portions 11 and 12 of the wire member effects a rotary movement of the latter, so that the relatively stationary lug 14 coöperates with the helices of the coil spring 10 for moving the pusher 9 longitudinally, thereby projecting the pencil-point 8, or permitting the latter to be 105 moved inward.

If the pencil is dropped so that its point

strikes upon the floor or other object, the helices of the spring 10 will yield so as to obviate the breaking of the point. Moreover, because of the yielding of the spring 10, the user is prevented from applying excessive pressure to the pencil-point, for when the user tends to bear excessively on the pencil-point, the yielding of the spring 10 compensates for such tendency. The combination of parts 7 to 14, inclusive, constitutes the lead holding and projecting means, and the parts 15 and 17 constitute the actuating unit or member to actuate the lead projector.

A receptacle 20 is fitted within the hollow manipulative member 15, and this receptacle comprises a tubular body having primarily open ends, so that a rubber eraser 21 can be fitted in the inner end, as illustrated in Fig. 2, and this member constitutes a bottom for the receptacle. The outer end of the receptacle may be closed by a screw threaded cap or cover 22. Slots 23 are provided in the wall of the receptacle 20, and the material between these slots may be slightly bowed so that they press outward against the inner surface of the hollow actuator 15 and effect a frictional engagement therewith for holding the receptacle in its place. However, when it is desired to remove the receptacle so that the eraser 21 may be used, it is only necessary to grasp the cap 22 and pull the receptacle out of the hollow actuator, through the hole in the rear end of the latter. It should be understood that a supply of pencil points may be stored in the receptacle 20, and that the slots 23 are sufficiently narrow to prevent the pencil points from passing out therethrough.

A modification of the receptacle for storing pencil points is shown in Fig. 5, and in this modification, the outer end of the receptacle 20' is closed by a metal disk 20^a which may be integral therewith, and has an outlet 20^b therethrough. A cap 20^c is pivotally mounted on the disk 20^a and has an aperture 20^d therethrough. The aperture 20^d may be brought into and out of registry with the aperture 20^b by turning the member 20^c on its pivot.

It is not intended to limit this invention to the exact details of construction and arrangement as specified and shown, but changes may be made within the scope of the inventive idea, as implied and claimed.

What I claim as my invention is:—

1. In a lead-pencil, a casing having a lug projecting inwardly thereof, said casing having an outlet at its front end, a pencil-point in said outlet, a pusher operable to project said pencil-point through said outlet, a helical coil of wire mounted for longitudinal movement in said casing to actuate said pusher, said lug having its inner end between two helices of said helical coil of wire, and means to rotate said helical coil

and thereby co-act with said lug in effecting said longitudinal movement of the pusher.

2. In a lead-pencil, a casing having a lug projecting inwardly thereof, said casing having an outlet at its front end, a pencil-point in said outlet, a pusher operable to project said pencil-point through said outlet, a helical coil of wire mounted for longitudinal movement in said casing to actuate said pusher, said lug having its inner end between two helices of said helical coil of wire, a longitudinally grooved rod having an axial bore in open communication with the longitudinal groove, and means to rotate said rod, said pusher being slidably seated in said axial bore, said helical coil being disposed around said rod and having one end extending into said groove to effect rotation of the helical coil with said rod, said helical coil also having one end in position to actuate said pusher.

3. In a lead pencil, a casing having an outlet at its front end, a sleeve formed with an inwardly extending lug and being secured to the inner surface of said casing, a pencil-point in said outlet, a pusher operable to project said pencil-point through said outlet, a helical coil slidably fitted in said sleeve and receiving said lug between two of its helices, and actuating means for rotating said helical coil, said means also holding said pusher in such position between said pencil-point and helical coil that the latter causes the pusher to project said pencil-point.

4. In a lead pencil, a casing having an outlet at its front end, a sleeve formed with an inwardly extending lug and being secured to the inner surface of said casing, a pencil-point in said outlet, a rod having a longitudinal groove and an axial bore in open communication with said groove, said rod being mounted for rotation within said casing and extending through said sleeve, and a wire member comprising a helical coil and a pusher, said pusher being seated in said groove and axial bore while said helical coil surrounds said grooved rod and is held against rotation relative thereto by its connection with said pusher, said helical coil being slidably fitted between said sleeve and grooved rod and serving to hold the latter axially aligned with said pencil-point, said lug extending between two helices of said coil and co-acting therewith to move said wire member longitudinally of the casing.

5. In a lead-pencil, a casing having a lug projecting inwardly thereof, said casing having an outlet at its front end, a pencil-point in said outlet, a pusher operable to project said pencil-point through said outlet, a helical spring mounted for longitudinal movement in said casing to actuate said pusher, said lug having its inner end between two helices of said helical spring, and means to

rotate said helical spring and thereby co-act with said lug in effecting said longitudinal movement of the pusher and thereby projecting and yieldingly holding the pencil-point.

6. In a lead-pencil, a tubular outer casing, an actuating unit, means co-acting with said outer casing and actuating unit to project the lead, and a lead-storing receptacle normally secured by friction in said actuating unit, said actuating unit including a hollow cylindrical portion and an annular manipulative portion, said cylindrical portion being rotatably secured in said outer casing, said manipulative portion being exposed exteriorly of said outer casing to permit it to be grasped and turned by the hand of the

user, said annular portion having at its outer end an opening sufficiently large to permit 20 said receptacle to be passed therethrough into and out of said actuating unit.

7. In a pencil, the combination of a casing, holding and projecting means therein, an actuating member rotatably secured in 25 the casing and projecting beyond one of its ends to provide a finger-piece whereby the member may be grasped and rotated to actuate the lead projecting means and a lead storing receptacle frictionally retained in said 30 member and insertible and removable through the open outer end of said member.

In testimony whereof I have hereunto set my hand.

JACOB HENRY STULL.
